UNITED STATES PATENT OFFICE.

HARRY C. ZIMMERMAN, OF WASHINGTON, DISTRICT OF COLUMBIA.

CRADLE FOR GUNS.

Application filed June 7, 1927. Serial No. 197,164.

(GRANTED UNDER THE ACT OF MARCH 3, 1883; 23 STAT. L. 625.)

The invention described herein may be used by the Government, or any of its officers or employees in prosecution of work for the Government, or by any other person in 5 the United States, without payment to me of any royalty thereon, in accordance with the act of March 3, 1883.

This invention relates to a cradle for guns.

In those guns wherein the cradle containing the recuperator chambers are forged from a single block the work can not be divided and a false step occurring during fabrication necessitates discarding of the entire piece.

15 With a view to facilitating the production of such units, reducing weight and permitting repair and replacement it is contemplated in the present invention to form a box cradle of shaped metal within which may be 20 assembled the cylinders of the recoil and counter-recoil mechanism.

A further object of the invention consists in the novel association with the cradle of a counter-recoil buffer.

25 With the foregoing and other objects in view, my invention resides in the novel arrangement and combination of parts and in the details of construction hereinafter described and claimed, it being understood that 30 changes in the precise embodiment of the invention herein disclosed may be made within the scope of what is claimed without departing from the spirit of the invention.

A practical embodiment of the invention 35 is illustrated in the accompanying drawing wherein:

Fig. 1 is a view in side elevation of a cradle assembly constructed in accordance with the invention;

40 Fig. 2 is a longitudinal sectional view through the recuperator cylinders on the line 2—2 of Fig. 3;

Figs. 3 and 4 are sectional views on the respective lines of Fig. 1;

45 Fig. 5 is a longitudinal sectional view of the counter-recoil buffer;

Fig. 6 is a sectional view on the line 6—6 of Fig. 5;

50 Fig. 7 is a view in rear elevation of the yoke.

Referring to the drawings by numerals of reference:

The cradle 5, in the form of a rectangular receiver, is composed of a pair of channel

shaped plates having their free edges in- 55 turned, the plate 6 being of greater depth to constitute the body and the plate 7 forming the cover and being of considerably less depth to establish a slide for receiving the guides 8 of the gun 9. The slide is provided 60 with liners 10 which are held in place by the rivets 11 connecting the cover and body.

Within the cradle is a hydro-pneumatic recuperator mechanism which consists of a recoil cylinder 12 and a recuperator or receiver cylinder 13 each threaded into a double chambered yoke 14 having a communicating passage 15 in its dividing wall 16. The yoke is secured to the cradle by means of the bolts 17. The forward ends of the tubes forming the cylinders 12 and 13 are provided with closures 12^a and 13^a having threaded engagements therewith. As seen in Fig. 1 the forward portions of the cylinders rest in a support block 18 and are held in position 70 by a pair of spacer blocks 19 and 20, all of said blocks being attached to the cradle by screw bolts 21.

The recoil cylinder contains a piston 22 attached to the gun lug 23 so that on recoil 80 of the gun the piston forces oil into the recuperator cylinder through the passage 15 to displace a floating piston 24 and compress air or a gas in the usual manner.

Referring to Figs. 1, 3 and 4 the forward 85 portion of the cover plate of the cradle is formed with a semi-circular depression 25 to seat a buffer cylinder 26 held by clamps 27 and occupying a position between the slides of the gun. Within this cylinder is a piston 28 arranged to be struck by the gun during the final portion of its counter-recoil movement to compress an actuating spring 29. The piston is hollowed for a portion of its length to receive an axial throttling bar 30 which is provided externally of the cylinder 90 with a handle 31 whereby it may be turned to vary the throttling orifice. The piston head is provided with an inclined passage 32 for establishing communication with the throttling bar and also the plurality of one- 95 way valves 33 for permitting unobstructed displacement of the braking fluid when the piston is moved to the rear under the influence of the spring.

100 I claim:

1. In a cradle for guns, a receiver comprising a body and a cover formed of channel-

- shaped plates having their free edges in-turned and secured to each other, the cover being of less depth to establish a gun slide, a double chambered yoke secured to the receiver and having a communicating passage between chambers, spaced cylinders threaded to the yoke and supporting means secured to the forward portion of the cradle and embracing the cylinders.
- 10 2. A cradle for guns including a channel shaped body, a cover secured to said body and forming a gun slide, a double chambered yoke secured to the body and having a communicating passage between chambers and a

plurality of cylinders threaded to the yoke. 15

3. In a cradle for guns, a receiver comprising a channel-shaped body plate and a cover therefor, a yoke secured to the rear end of the body and a plurality of cylinders threaded to the yoke. 20

4. In a cradle for guns, a receiver, a cover plate for said receiver formed with a rounded depression, a cylinder seated in said depression and clamped to the cover and a counter-recoil buffer mechanism in said cylinder. 25

HARRY C. ZIMMERMAN.
